UNITED STATES PATENT OFFICE.

JOSEPH W. KARNER, JR., OF NEW YORK, N. Y.

GAS GUN.

Application filed November 7, 1924. Serial No. 748,316.

The invention relates in general to certain improvements in a gun of general application designed to fire any kind of a projectile, and the invention specifically relates to a gun preferably in pistol form and designed to discharge a gas or volatile projectile by the firing of cartridges containing gas producing substances.

More definitely defined the invention relates to firing mechanism in a gun of the type described and to an improved form of trigger control for such mechanism.

The primary object of the invention is to provide a simple form of gas gun which will be positive in its actuation, which can be easily and cheaply constructed and which at the same time will feature a neat, well balanced form of pistol simulating a conventional form of pocket revolver. The invention contemplates the providing of a fire arm which will accommodate a plurality of cartridges and which will fire the cartridges from a fixed position successively by the manipulation of a single trigger mechanism which may be actuated repeatedly and until all the cartridges have been exploded.

Another object of the invention is to provide a type of gun, particularly applicable when the gun is in the form of a pistol, in which the cartridge carrying clip is a readily replaceable unit with each cartridge positioned in its own charge directing barrel and in which each barrel is distinct from each other barrel and otherwise designed to insure separation of the several fired charges until they are each cleared of the gun.

Incidental to the last object, it is a further desideratum of the invention to provide a gas gun the several parts of which are designed to insure gas tight connections between all the parts to prevent leakage, except at the discharge end of the several barrels.

Various other objects and advantages of the invention will be in part obvious from an inspection of the accompanying drawings and in part will be more fully set forth in the following particular description of one form of mechanism embodying my invention, and the invention also consists in certain new and novel features of construc-

tion and combination of parts hereinafter set forth and claimed.

In the accompanying drawings:

Figure 1 is a plan view looking down upon a pistol illustrating a preferred embodiment of the invention;

Figure 2 is a vertical sectional view taken on the medial line and on the line 2-2 of Figure 1 showing the hammer in its normal inoperative position after it has fired the upper firing pin;

Figure 3 is a view in front end elevation looking at the left hand side of the device shown in Figure 1.

Figures 4 and 5 are similar views of the firing mechanism, and in which Figure 4 is a view showing the hammer in retracted position just prior to being released; Figure 5 showing the trigger in its final position, and the hammer released to its firing position;

Figure 6 is a horizontal sectional view taken through the upper portion of the gun and taken on the line 6-6 of Figure 3;

Figure 7 is a vertical sectional view taken on the line 7-7 of Figure 3;

Figure 8 is a horizontal sectional view taken on the line 8-8 of Figure 4; and

Figure 9 is a detailed transverse sectional view taken on the line 9-9 of Figure 4, in each case looking in the direction indicated by the arrows.

In the following description and in the claims, parts will be identified by specific names for convenience of expression but they are intended to be as generic in their application to similar parts as the art will permit.

In the drawings there is shown a hand pistol comprising a stock 10, provided with handle 11, finger trigger 12, trigger guard 13, all somewhat resembling a known form of hammerless revolver. The stock is hollow to provide a closed compartment 14 for accommodating firing mechanism 15 actuated from a trigger mechanism which trigger mechanism includes the trigger proper 12. The forward position of the stock forms, between the two outlining and upstanding walls 17 and 18 thereof, a barrel receiving recess opened at the top and at its forward end. The rear end of this recess is defined by an upstanding block 19 hereinafter referred to as a breech

block which acts as a spacing block between the walls 17 and 18, defines the front end of the chamber 14, the rear end of the barrel clip recess, and is made resilient to provide some recoil cushioning effect.

Removably inserted in the recess thus formed in the front end of the stock is a combined cartridge carrying clip and barrel unit 20. The unit is intended to be readily mounted and demounted from the stock and is slidably inserted in position by a vertical movement. A slot and groove connection 21 is provided to guide the unit into place and a spring pressed latch 22 acts to lock the unit in position. The unit is intended to include a plurality of barrels 23, three being shown in the drawings, but it is intended that the units shall contain the maximum number of barrels that can be carried conveniently, taking into consideration the character of cartridge which each barrel is designed to carry and taking into consideration the convenient weight of the device as a whole.

In the device illustrated the barrels are designed to receive cartridges containing a gas forming substance. In order to prevent leakage, the present disclosure features a gas tight connection between the unit 20 and the stock so as to minimize any accidental leakage rearwardly from the gun.

Mounted in the breech block 19 is a plurality of firing pins 24, one for each of the barrels and each operatively disposed to fire the cartridge carried in its associated barrel. The pins are slightly longer than the breech block, extend transversely therethrough and are spring pressed rearwardly, each by means of a spring 25 designed normally to project the rear end 26 of its associated pin into the chamber 14 and in position to be engaged by a firing hammer 27 forming part of the firing mechanism. An enlargement 28 on each pin forms a bearing for one end of the spring 25 and limits the rearward movement of the pin under action of the spring.

The pins are selectively moved into their firing positions by means of the single firing hammer which is pivotally mounted at its lower end upon a rocking pin 29 for rocking movement in the medial plane of the piston. The hammer is formed of two main parts, a triangular shaped lower supporting lever 30 on the top flat side 31 of which is rotatably mounted a cylindrical barrel portion 32. The cylindrical portion is rotatably secured in its mounted position by means of an overhanging L-bracket 33 and which additionally acts to provide an upper bearing 34 for the cylinder 32. The upstanding rear portion 35 of this bracket also provides an engaging post for a strong firing spring 36 the upper end of which bears against the hammer and the lower end of

which is removably secured to the stock at 37 as shown more particularly in Figure 2. A supplemental firing spring, in this case shown to be a coiled spring 38 is positioned between the fixed bracket part 33 and the stock at the upper portion of the hammer.

The cylindrical portion 32 of the hammer is provided with a plurality of pin receiving apertures 39 arranged in staggered relation considered both circumferentially and longitudinally of the barrel and designed so that when the hammer is in position to engage any one of the firing pins, then the apertures are so located that every other firing pin will project into one of the apertures. The apertures are so disposed that upon each step of a step-by-step rotation of the hammer hereinafter described, the cartridges in the several barrels are fired consecutively until with either a complete or fractional rotation of the hammer all of the cartridges will have been fired.

The hammer portion 32 is rotated in its step-by-step movement by means of a pawl and ratchet form of progressive feed. The ratchet element is provided by means of a series of slots 40 formed in a reduced portion 41 of the cylinder 32 to form a slip tooth construction, such as is shown in Fig. 8. The teeth 42 so formed are disposed in the path of movement of a ratchet, in Fig. 2 shown to be a lever 43 with a nose end 44 for engaging the teeth of the ratchet and maintained in releasable position by means of a pawl controlling spring 45. It is understood from this construction that the movement of the hammer from the normal position in Fig. 2 into the retracted position shown in Fig. 4 will cause the tooth which at the time is facing the nose 44 to move into engagement with the relatively fixed nose causing the same to react upon the cylinder 32 and to rotate the same one step in its rotary movement.

The hammer is moved from its normal position shown in Fig. 2 into its retracted position shown in Fig. 4 and the springs 36 and 38 put under tension by the engagement therewith of the trigger mechanism in its firing movement. This trigger mechanism includes the finger piece pivotally mounted on the rear portion of which is a push lever 46 having a rear hammer engaging end 47 and normally raised in the elevated position shown in Fig. 2 by means of a spring 47. The end 47 is caused to ride down a wedge shaped guide piece 48 formed on the underside of the breech block 19 and is moved by the action of the finger piece into engagement with a contact face 49 formed on the upper front side of the lever 30. As the trigger moves into its limiting position shown in Figure 4, the guide 48 acting on the push lever 46 pushes the same off the bearing face 49 and causes the end 130

47 to release itself from the trigger and to pass into the undercut release 50 defining the lower front side of the lever 30. Releasing the hammer from the holding effect of the 5 trigger mechanism permits spring 36 or springs 36 and 38 where spring 38 is used to react forcefully on the hammer and move the same from the retracted position shown in Fig. 4 into firing position shown in Fig. 10 ure 6 and into engagement with one of the firing pins.

A suitable safety catch indicated at 51 is disposed to prevent retreat of the hammer and subsequent possibility of firing the 15 device accidentally.

It is understood that the barrel unit may be replaced by a similar unit and the same pistol may be used repeatedly by inserting another clip with fresh cartridges for the 20 previously fired clip with its dead cartridges. It is also within the scope of the disclosure to substitute for the clip illustrated other clips with different size and character of barrels so that with the unitary pistol car- 25tridges of different sizes may be employed or different kinds of cartridges may be used, as where it may be desired in the successive operations of the trigger to fire different forms of gases and eventually to fire a solid 30 projectile.

By means of the device disclosed any desired sequence of projected material may be employed simply by selecting the proper charge clip to give the results desired. Any 35 selected combination of projectiles may be fired simply by the successive operation of the trigger.

While I have shown and described, and have pointed out in the annexed claims, cer- 40 tain novel features of my invention, it will be understood that various omissions, substitutions and changes in the form and details of the device illustrated and in its opera- 45 tion may be made by those skilled in the art without departing from the spirit of the invention.

Having thus described my invention, I claim:—

1. In a gas gun, the combination of a 50 stock, a combined cartridge clip and barrel unit demountably inserted in the stock, a breech block provided with a plurality of firing pins, arranged in superposed order one above the other and one for each car- 55 tridge carried by the unit, a spring actuated hammer rockably mounted and housed in the stock and adapted when released to en- 60 gage the pins, a trigger having a push lever carried thereby and adapted to engage the hammer to set the same, a guide for said 65 push lever, said rocking hammer being also mounted for rotary movement and provided with circumferentially spaced notches forming a ratchet and a pawl adapted to engage in the notches as the hammer is rocked to

rotate the hammer with a step-by-step move- 70 ment.

2. In a gun, the combination of a stock, provided with a recess for receiving a barrel, a breech block defining the rear end of the 75 recess, a firing pin carried by the breech block and extending therethrough, a hammer rockably and rotatably mounted in rear of the breech block and adapted to be rocked into engagement with the pin, said hammer having an operative and an inoperative ro- 80 tative position relative to said pin and trigger controlled means operatively connected to the hammer for moving the same to and from said operative positions.

3. In a gun, the combination of a plu- 85 rality of barrels, each adapted to receive a cartridge, a plurality of firing pins, one for each barrel, a spring actuated, pivotally mounted hammer for moving the pins on their firing stroke, said hammer also mounted for rotary movement and provided with means adapted to be rotated into po- 90 sitions successively to engage the different firing pins, said last named means including a step-by-step pawl and ratchet hammer rotating means and a trigger mechanism operatively connected to actuate said step- 95 by-step means and for actuating the ham- mer in its pin firing movements above its pivotal mounting.

4. In a gun, the combination of means for receiving a plurality of cartridges in firing 100 positions, a firing mechanism including a hammer of cylindrical form pivotally mounted for rocking movement to and from its firing position, said hammer also mounted for rotary movement about its lon- 105 gitudinal axis, said cylindrical hammer pro- 110 vided with circumferentially spaced parts for successively facing the cartridges as the hammer is rotated whereby the cartridges are fired successively by the successive rock- 115 ing and rotary movements of the hammer.

5. In a gun, the combination of a plurality of barrels, each adapted to receive a car- 120 tridge, a plurality of firing pins, one for each barrel, a spring actuated, pivotally mounted hammer for moving the pins on their firing stroke, said hammer also mounted for rotary movement and provided with means controlled by the rocking move- 125 ment of the hammer and adapted to be ro- 130 tated into positions automatically to engage the different firing pins successively.

6. In a gun, the combination of a hammer pivotally mounted for movement to and from a firing position, a spring bearing directly on the hammer in spaced relation to its pivotal mounting for swinging the same about its pivotal mounting and for moving the hammer on its firing movement, said hammer having a plurality of firing positions and trigger actuated mechanism operatively connected for placing the spring under ten-

- sion and for moving the hammer successively into its several firing positions and means controlled by the movement of said mechanism into its final position for releasing 5 the same automatically from the hammer and for permitting the spring to react on the hammer and move the same into its firing position.
7. In a gun, the combination of a cylindrical hammer pivotally mounted for movement to and from a firing position, said hammer mounted for rotary movement about an axis intersecting the axis of its pivotal movement and having on the side 10 15 a plurality of circumferentially firing pin engaging points and trigger controlled mechanism for moving the hammer from its firing position and automatically causing it to rotate with a step-by-step pawl and ratchet movement and spring controlled means for moving the hammer on its firing stroke when free of said trigger controlled mechanism.

8. In a gun, the combination of a cylindrical hammer pivotally mounted for move- 20 25

ment to and from a firing position, said hammer mounted for rotary movement about an axis intersecting the axis of its pivotal movement and having on the side thereof a plurality of recesses forming therebetween a plurality of firing points and trigger controlled mechanism for moving the hammer from its firing position and automatically causing it to rotate with a step-by-step movement. 30

9. In a gas gun the combination of a plurality of firing pins, a spring actuated hammer mounted for rocking movement about a pivotal mounting, said hammer including a pin engaging barrel mounted for 40 rotary movement about its axis in addition to its rocking movement, said axis extending at right angles to the axis about which the hammer rocks, and said barrel provided with means to successively engage the firing 45 pins.

Signed at N. Y. city, in the county of New York and State of New York this 22d day of July A. D. 1924.

JOSEPH W. KARNER, JR.
